UNITED STATES PATENT OFFICE.

ANTAL NIDERMAJER, OF ROSSFORD, OHIO.

DESIGN FOR A FRUIT-STAND.

43,675.

Specification for Design.

Patented Mar. 4, 1913.

Application filed October 11, 1912. Serial No. 725,319. Term of patent 7 years.

To all whom it may concern:

Be it known that I, ANTAL NIDERMAJER, a subject of the King of Hungary, residing at Rossford, in the county of Wood and State of Ohio, have invented a certain new, original, and ornamental Design for Fruit-Stands, of which the following is the specification, reference being had to the accompanying drawing, forming part thereof.

Figures 1 and 2 are respectively an elevation and plan, the latter being upon a re-

duced scale with respect to the scale of Fig. 1, of a fruit stand illustrating my new design.

I claim—

The ornamental design for fruit stands, as shown.

ANTAL NIDERMAJER.
